UNITED STATES PATENT OFFICE.

THOMAS A. GEBHARDT, OF RICHMOND, VIRGINIA.

SCREEN-CLOSURE.

1,087,757.

Specification of Letters Patent. Patented Feb. 17, 1914.

Application filed August 28, 1912. Serial No. 717,593.

To all whom it may concern:

Be it known that I, THOMAS A. GEBHARDT, a citizen of the United States, residing at Richmond, in the county of Henrico and State of Virginia, have invented new and useful Improvements in Screen-Closures, of which the following is a specification.

This invention relates to screen closures for windows, doors or other similar openings and the principal object of the invention is to improve upon the structure illustrated in my copending application Number 645,703, which was filed August 24, 1911. In this application an exit was so formed in the frame as to permit the flies to escape but no means was provided for reinforcing the fabric supporting strip which extended across the frame at the exit opening.

It is a further object of this invention to avoid this difficulty and to also provide a screen in which the fabric is secured to the frame without fastening devices, such as tacks, screws, and the like, or in other words, so that when the retaining strips are removed, the fabric may be taken out and discarded and a new piece of fabric inserted and secured in the frame without tacking the same.

Further objects of this invention will appear as the following specific description is read in connection with the accompanying drawing, which forms a part of this application, and in which:

Figure 1 is an outside elevation. Fig. 2 is a vertical sectional view on the line 2--2 of Fig. 1. Fig. 3 is a detail horizontal section taken on the line 3--3 of Fig. 1.

Referring more particularly to the drawing, 1 represents a frame which is constructed, as is usual, of the vertical stiles 2 and the top and bottom rails 3 and 4. Each of the vertical stiles 2 and the bottom rail 4 is provided with a rabbet 5 having a depending groove 6 in its base which is adapted to receive the screen fabric 7. The two sides and the bottom of the screen fabric are secured in this groove and in the rabbet by means of retaining strips 8 which are provided with ribs 9 to enter and force the fabric into the groove.

The upper rail is cut away, as shown at 10 intermediate its length and bridged across

the face of the rail and across the recess formed is a retaining strip 11 which is held down upon the rail by any suitable type of fastening device, such as the screws 12 shown. The upper edge of the fabric is passed in between the U-shaped retaining strip 13 formed of any suitable metal which is folded over upon the face of the fabric and apertured to receive the fastening screws 12. The clamping strip 13 and the retaining strip 11 are held away from the wall by means of a spacing sleeve 14, through which one of the retaining screws 12 passes. By beveling the outer and under faces of the upper rail 3 so as to separate the stile from the supporting strip there is produced an exit opening which extends approximately entirely across the frame, being only interrupted by the spacing sleeve 14.

What is claimed is:

In combination a rectangular frame, one end of said frame having a portion beveled inwardly and rearwardly whereby a recess is formed, the opposite end of said frame being formed with a transversely-extending rabbed portion terminating in a right-angular recess, a foraminous sheeting having one end completely overlying the edges of said recess and rabbed portion, an L-shaped strip seated in said recess and rabbed portion whereby said sheeting is held in firm position, a relatively narrow strip spanning said first-named recess and being secured at its ends to said frame, a U-shaped metallic member secured alongside of said strip throughout its length and having its folds arranged close together, said sheeting having its free end disposed between said folds and overlying said U-shaped member, said strip being spaced from said beveled portion, a tubular spacing member interposed between said U-shaped member and said beveled portion, and a screw passing through said strip, doubly through said sheeting, into said spacing member and terminating in said frame.

In testimony whereof I affix my signature in presence of two witnesses.

THOMAS A. GEBHARDT.
